UNITED STATES PATENT OFFICE.

HARRY E. PHELPS, OF BROOKLYN, NEW YORK, ASSIGNOR TO C. KENYON COMPANY, INC., OF BROOKLYN, NEW YORK, A CORPORATION OF NEW YORK.

COUPLING.

1,398,276.

Specification of Letters Patent. Patented Nov. 29, 1921.

Application filed December 13, 1919. Serial No. 344,538.

To all whom it may concern:

Be it known that I, HARRY E. PHELPS, a citizen of the United States, residing at 839 East 19th St., Brooklyn, in the county of 5 Kings and State of New York, have invented certain new and useful Improvements in a Coupling, of which the following is a specification.

My invention relates to a new and improved coupling for supplying air under pressure to the air bags used in the manufacture of the casings or shoes for automobile tires.

As is well known, these casings or shoes 15 consist of a combination of fabric and rubber made up in various ways according to the particular type of casing desired to be manufactured.

In the vulcanizing or curing of these casings, it is of course necessary to subject them 20 to a temperature which causes the softening or melting of the rubber, and it is therefore necessary to keep these casings under great pressure during the vulcanization period, so 25 that the complete and cured shoes should have the predetermined shape desired.

For this purpose, pneumatic air bags or inner tubes have been used for many years and to keep these air bags in proper shape 30 during the curing process, air has been supplied to them under great pressure, as high as two hundred and fifty pounds per square inch, and this air has become heated as a result of the necessary temperature for the 35 vulcanizing process.

The great pressure and heat of the air in these air bags has made the problem of manufacturing the necessary couplings one of great technical difficulty. It is impossible to 40 use washers for making the coupling airtight, with any degree of efficiency, because the heat to which these couplings are subjected is so great that ordinary washers burn up after having been used a few times.

45 It has been universal practice in the art to use unions connected by threading for making the necessary connections, and this expedient has been recognized for many years as being unsatisfactory, as the making 50 of the necessary connections took a great deal of time and the arrangement was a very clumsy one.

According to my improved construction a very reliable and simple connection or coupling is provided, which can be thrown into

and out of operation by a turn of a lever and which may be independent of any washers if this is desired.

Other objects of my construction will be shown in the following description and 60 drawings which illustrate a preferred embodiment thereof.

Figure 1 is a side elevation partially in section.

Fig. 2 is an end elevation. 65

Fig. 3 is an end elevation showing the side opposite to that depicted in Fig. 2.

Fig. 4 is a central vertical section.

Fig. 5 is a section along the line 5—5 of Fig. 1. 70

As shown more particularly in Figs. 1 and 4, the connecting members of my improved coupling consist of an entering part 1 and an entered part 2. A pipe 3 leading to the source of heated air under pressure is 75 threaded or connected in any other suitable manner to the entered member 2 and pipe 41 is also threaded or secured in any other suitable manner to the entering member 1. 80

The entering member 1 has a seat portion 4 which is preferably conical in form, and which is ground so as to afford a very tightly fitting seat for the adjacent part of the entered member 2, which should be 85 of exactly the same shape and which is also ground so as to provide tight fit with the seat portion 4 when the entered member and the entering member are pressed together with sufficient force. 90

As shown more particularly in Fig. 4, the entering member 1 has a projection 5 which projects from the seat portion 4.

A movable bridge 6 is slipped over the pipe 41 before the cross-pipe 7 is secured thereto, and this bridge 6 is adapted to abut firmly against the base of the entering member 1, and is adapted to revolve around the pipe 41. 95

The bridge 6 as shown more particularly 100 in Figs. 4 and 5 is provided with a nose 8 and a fork 9.

A link 10 having a forked top as clearly shown in Fig. 2 is pivoted by any suitable means at 11 to the entered member 2, and 105 the other side of the entered member 2 is formed into a hook 12 which is adapted to fit under and against the nose 8, and abut against the flange 14 of the said nose 8.

The bridge 6 and the part of the entered 110

member 2 directly above it may be called the fastening members because they enable the entered member and the entering member to be fastened together and the link 10, 5 the hook 12 and the lever 15 which is later more specifically described, may be called the locking members because they lock the fastening members together.

It is to be noted, as seen in Fig. 5 for example, that the entered member and the entering member may slightly shift or move relatively to one another when the parts have been finally locked by moving the lever 15 to the position shown in Fig. 1.

15 This enables the seat portions of the entered member and the entering member to have proper contact and be firmly pressed one against the other even though their initial position, as the locking operation is being completed, is such as to have the seat portions slightly out of line. This shifting movement is very slight, but it is sufficient in actual practice to secure efficient operation of the parts.

25 A cam lever 15 is pivoted at 16 to the link 10 as clearly shown in Figs. 1 and 2, and is provided with a top whose curvature is so proportioned to the curvature of the bottom of the fork 9, that by forcing the cam lever 30 15 from the position shown in dotted lines in Fig. 4, to the position shown in full lines while the hook 12 is underneath the nose 8, the entered member 2 and the entering member 1 can be forced together very 35 powerfully so that their corresponding portions are forced together so as to fit very tightly. The parts can be made of any suitable metal or alloy which may have a very slight yield when the force is applied by the 40 operation of the cam lever 15 so as to insure the tightest possible fit at the seat portion 4 and the correspondingly shaped seat portion of the entered member 2.

The operation of my device is as follows:—

The bridge 6 is slipped over the pipe and is held either in the position shown in Fig. 4, when it is substantially parallel to the cross pipe 7, or it can be swung as shown in 50 dotted lines in Figs. 4 and 5 until it is at right-angles to this position.

Of course, the bridge can be revolved so as to present any desired angle to the pipe 7 which leads to the pneumatic cores.

55 The lever 15 is then held substantially at right angles to the pipe 41 and is revolved inwardly and toward the pipe 41 so that its cam top can just pass under the toe 20 of the fork 9.

60 The lever 15 is then revolved around the pivot 16 until it is in the position shown in Fig. 4 and substantially parallel to the pipe 41, the action of the cam top of lever 15 producing a very powerful forcing together 65 of the entered member and the entering

member, due to the fact that the hook 12 fits under the nose 8 and abuts the flange 14.

As shown more particularly in Fig. 3, the bottom of the hook 12 is wider than the nose 8, so that this furnishes additional security 70 in case the workman is careless about putting the parts into the proper position.

Due to the downwardly projecting toe 20 of the bridge 9, the cam action of the top of the lever 15 automatically locks it into the 75 vertical position shown in Fig. 4, so that there is considerable resistance to any careless displacing of the parts from the operative position shown in Fig. 4.

It is impossible to place the parts into inoperative position without revolving the lever 15 into a substantially horizontal position, so that its top can clear the toe 20.

By the arrangement and combination of parts above described, it is possible to make 85 a connection or coupling very quickly and with a minimum of skilled labor and the parts can be used over and over again without the need of any washers being used, if this is desired.

90 I have shown a preferred embodiment of my invention but it is clear that numerous changes and omissions could be made without departing from its spirit and I do not desire to be limited to the details herein described as these could be varied and omitted without departing from the spirit of my invention.

I claim:—

1. A coupling for the air bags used in the 100 vulcanization of the casings of pneumatic tires, comprising an entered member and an entering member having co-acting seat portions of substantially unalterable form and fastening means for said members including 105 co-acting parts capable of movement with said members, and constituting the sole means for enabling said members to be forcibly drawn together and held in locked position.

110 2. A coupling for the air bags used in the vulcanization of the casings of pneumatic tires, comprising an entered member and an entering member having engaging seat portions of substantially unalterable form and 115 fastening means for said members including co-acting parts capable of movement with said members, and constituting the sole means for enabling said members to be forcibly drawn together and held in locked 120 position, said parts being free to be relatively shifted as said members are drawn together.

3. A coupling for the air bags used in the vulcanization of the casings of pneumatic tires, comprising an entered member and an 125 entering member having seat portions made of hard unyielding material, of fastening means for said members having two complementary parts, each said part being associated with one of said members, said 130

- parts being relatively movable with respect to each other in a plane perpendicular to the common axis of said members before they are locked in their final position, the 5 said complementary fastening parts being capable of being relatively moved so as to draw said members together with varying force, and locking means of such configuration that they tend to remain in the position 10 in which said members are drawn together with the maximum force to which they have been subjected by said locking means.
4. A coupling for the air bags used in the vulcanization of the casings of pneumatic 15 tires and comprising an entered member and an entering member having coacting seat portions of substantially unalterable form, fastening means associated with the said members including a bridge fulcrumed on 20 one of said members and movable with the other member and locking means including a revoluble cam member coöperating with the bridge for forcing the said fastening means together so as to forcibly draw the 25 said members together and hold them in locked position.
5. A coupling for the air bags used in the vulcanization of the casings of pneumatic tires, comprising an entered member and 30 an entering member having coacting seat portions of substantially unalterable form, and fastening means for said members including a fulcrumed bridge independent of said members and co-acting parts capable of 35 movement with said members, and constituting the sole means for enabling said members to be forcibly drawn together and held in locked position.
6. In a coupling for the air bags used in 40 the vulcanization of the casings of pneumatic tires, the combination of an entered member capable of having a pipe secured thereto and having one of its ends shaped into a hook-like form, an entering member 45 having a pipe secured thereto, a perforated bridge capable of being slipped over the said pipe, the said hook-like end being adapted to slip under the nose of the said bridge to form a fulcrum for the bridge, 50 and means carried by the other end of the said entered member adapted to coöperate with the other end of the said bridge so as to cause the said two members to be tightly forced against each other, said members being relatively shiftable as they are forced 55 together.
7. In a coupling for the air bags used in the vulcanization of the casings of pneumatic tires, the combination of an entered member 60 capable of having a pipe secured thereto and having a laterally tapered hook-like end, an entering member having a pipe secured thereto, a perforated bridge capable of being slipped over the said last mentioned pipe 65 so as to be freely revolved thereon, the nose of the said bridge being provided with a lateral flange, the said hook-like end being adapted to be moved under the said nose to abut against the said flange, the other end of the said entered member having a 70 link pivoted thereto, the said link having a cam lever pivoted thereto, the said cam lever being adapted to coöperate with the other end of the said bridge which is of a fork-like shape, so as to force the said entered member and the said entering member 75 tightly together, the said link passing between the arms of said fork-like end when the parts are in operative position.
8. In a coupling for the air bags used in 80 the vulcanization of the casings of pneumatic tires, the combination of an entered member capable of having a pipe secured thereto and having a laterally tapered hook-like end, an entering member having a pipe 85 secured thereto, a perforated bridge capable of being slipped over the said last mentioned pipe so as to be freely revolved thereon, the nose of the said bridge being provided with a lateral flange, the said hook-like end being 90 adapted to be moved under the said nose to abut against the said flange, the other end of the said entered member having a link pivoted thereto, the said link having a cam lever pivoted thereto, the said cam lever 95 being adapted to coöperate with the other end of the said bridge which is of a fork-like shape, so as to force the said entered member and the said entering member 100 tightly together, the said link passing between the arms of said fork-like end when the parts are in operative position, the said fork-like end having a toe at the bottom thereof which hinders the displacement of the said cam lever unless it is first 105 revolved out of operative position.
9. A coupling for the air bags used in the vulcanization of the casings of pneumatic tires, comprising an entered member and an entering member having coacting and substantially unalterable seat portions of a substantially conical shape and locking means for locking the said members together, said locking means permitting a slight shifting of said members when their locking force 110 is exerted, the said locking means being of such configuration that they tend to remain in the position in which the said members are locked together with the greatest force, the force exerted by the said locking means 115 being taken up solely by the said substantially conical seat portions.
10. A coupling comprising a unit composed of a single entered member and a single entering member having coacting 120 metal seat portions of substantially unalterable form, all of said seat portions being tapered and of substantially the same contour, whereby when the entering member is forced into the entered member, the seat 125

portion of said entering member has a wedge-like action upon the seat portion of the entered member and tends to outwardly spread the seat portion of the entered member, the movement of said entered member into said entering member being very small and being limited by the resiliency of the seat portions of said members and manually-operated means connected to said members for forcing said entering member into said entered member, said means being of such structure that they tend to remain in

the position into which they have been forced and in which the entering member is urged with the greatest force into said entered member so as to then act as a lock, the said manually-operated means being so connected to said members that they permit a slight relative shifting of said members during the movement of said means to locking position. 15 20

In testimony whereof I hereunto affix my signature.

HARRY E. PHELPS.
